4 Claims. (Cl. 98—37)

The present invention relates to a novel ventilator structure, and more specifically to a ventilator of the type adapted to be installed in the wall of a building.

An important object of the present invention is to provide a novel ventilator structure especially suitable for installation in a vertical outside wall of a building for promoting the flow of air therethrough regardless of wind direction while minimizing the possibility of rain water and the like passing therethrough.

Still another important object of the present invention is to provide a novel ventilator structure which may be used close to or in abutting relationship with similar ventilator structures in order to provide a pleasing design or appearance and improved ventilation.

A further object of the present invention is to provide novel ventilator structure of the above described type which is of rugged and long lasting construction and may be economically fabricated from sheet material.

Other objects and advantages of the present invention will become apparent from the following description and the accompanying drawings, wherein:

FIG. 1 is a perspective view showing a ventilator incorporating the features of the present invention;

FIG. 2 is a rear elevational view, partially broken away, showing a ventilator incorporating features of the present invention;

FIG. 3 is an enlarged fragmentary sectional view taken along line 3—3 in FIG. 2;

FIG. 4 is an enlarged sectional view taken along line 4—4 in FIG. 1;

FIG. 5 is an enlarged sectional view taken along line 5—5 in FIG. 1;

FIG. 6 is a fragmentary perspective view of a central portion of the structure shown in FIG. 2; and

FIG. 7 is an enlarged fragmentary sectional view taken along line 7—7 in FIG. 1.

Referring now more specifically to the drawings, wherein like parts are designated by the same numerals throughout the various figures, a ventilator structure 10 incorporating features of the present invention is shown, which ventilator is adapted to be mounted within a wall or partition of a building. While it is to be understood that the ventilator may be installed at various locations in a building structure, it is especially suitable for installation in a vertical outside wall.

The ventilator 10 comprises an outer shell 12 preferably formed from sheet metal and including opposite upstanding side panels 14 and 16 and top and bottom wall panels 18 and 20. As shown in FIGS. 2, 4 and 5, inner margins of the side and top and bottom wall panels terminate in inturned flanges 22, 24, 26 and 28, which add strength and rigidity to the structure.

Mounted within the shell 12 are louver units 30, 32 and 34. It is to be noted that the louver units have a rectangular configuration the same as the rectangular configuration of the shell 12 except that each succeeding louver unit has smaller outside dimensions than the preceding unit and is nested within the preceding unit. It is important to note that this arrangement provides the ventilator structure with a symmetrical appearance and enables two or more of the structures to be used in substantially abutting relationship or in any desired pattern for providing the installation with a pleasing design and appearance as well as the desired ventilation.

2

The outer or largest louver unit 30 comprises vertical side sections 36 and 38 and top and bottom sections 40 and 42, respectively, extending along the opposite side walls or panels and top and bottom walls or panels of the shell 12. As shown best in FIGS. 4 and 5, each of these louver sections has an outer marginal portion terminating in a reversely bent flange 44. The forward marginal portions of the shell side and top panels 14, 16 and 18 are formed with downwardly offset sections 46 for accommodating the inturned flanges 44 of the louver sections associated therewith. With this arrangement the forward edges of the ventilator structure are substantially sealed along the opposite sides and the top by the inturned flange 44, and the outer surfaces of these flanges and the opposite sides and top panel of the shell 12 are coplanar so as to fit easily within a desired opening in a building wall. The flanges 44 of the louver unit 30 may be secured to the adjacent parts of the structure by welding or by a plurality of screws 48, if desired.

Each of the side, top and bottom sections of the louver unit 30 includes a relatively wide portion 50 which is inclined inwardly and rearwardly from adjacent its outer marginal flange 44. In addition each of these louver sections has an inner marginal portion 52 extending inwardly substantially in a plane perpendicular to the axis of the ventilator structure and terminating in an outturned flange 54.

In order to support the louver unit 32, channel members 56 are secured by means of screws 58 or other suitable devices against the inner surface of the inner marginal portion 52 of opposite side sections of the louver unit 30. In the embodiment shown, two of the channel members 56 are provided and are horizontally arranged in vertically spaced relationship. The louver unit 32 is substantially identical in construction and configuration to the louver unit 30 except that it is smaller in transverse dimensions and also in axial length. Thus the louver unit 32 includes side, top and bottom sections, each of which has a main portion 60 inwardly offset from and substantially parallel to a portion 50 of the louver unit 30. In addition each of the aforementioned sections of the louver unit 32 has an inner marginal portion 62 corresponding to the inner marginal portions 52 of the louver unit 30, and an outer marginal portion 64. The inner marginal portion 62 of the upper and lower sections of the louver unit 32 are secured to the channels 56 by screws 66 so that the louver unit is securely supported and positioned centrally within the louver unit 30. It is to be noted that the outer marginal portions 64 of the louver unit 32 are located axially within the outer marginal portions of the louver units 30.

The louver unit 34 also includes opposite side and top and bottom sections having main portions 68 substantially parallel and offset inwardly from the portion 60 of the louver unit 32, inner marginal portions 70, and outer marginal portions 72 corresponding generally to the aforementioned inner and outer marginal portions 62 and 64. In order to support the louver unit 34, channel members 74 are secured in horizontally and vertically spaced apart relationship by means of screws 76 to inner marginal portions of the louver unit 32 and by screws 78 to the inner marginal portions of the louver unit 34.

With the arrangement of the rectangular louver units described above, it is to be noted that the ventilator is provided with rectangular slots or openings. Thus, each opening has an outer end or mouth presenting portions facing diagonally outwardly in opposite directions as well as diagonally upwardly and downwardly. In other words, the louver arrangement provides for air scoops facing in different directions whereby the ventilator effectively directs air therethrough substantially regardless of the direction of the wind.

If desired, the central opening defined by the inner marginal portions of the louver unit 34 may be closed by a cap 80. In the embodiment shown, the cap 80 overlies the inner marginal portion 70 and is secured in position by means of a strap 82 which is fixed to the cap and has inner end portions 84 bent around edges of the channel members 76.

In order to prevent the passage of rain water and the like through the ventilator unit, baffles 85, 83 and 90 are horizontally disposed and vertically spaced between opposite sides 14 and 16 of the shell and behind the louver units. As shown best in FIG. 5, the baffles extend forwardly and downwardly from adjacent rear edges of the shell and substantial spaces are provided between the baffles for promoting the free flow of air therebetween. Preferably the upper edge of the baffle 90 is located slightly below the inner margin of the upper section 40 of the outer louver unit 30. The baffle 90 positioned in this manner effectively prevents the passage of rain while leaving a substantial upper section of the opening defined by the inner margin of the shell unobstructed. The baffles may be welded to the shell or detachably connected thereto by suitable means such as screws 92.

It is to be noted that while the upper baffles 83 and 90 have downturned lower margins spaced inwardly from the louver units, the lowermost baffle 86 extends beneath and in parallel slightly spaced relationship with respect to the lower section 42 of the outer baffle unit 30. Furthermore, as shown in FIG. 5, and in greater detail in FIG. 7, the bottom wall 20 of the shell has a forward marginal upstanding flange 94 spaced inwardly from the front edge of the ventilator structure. The lower margin of the baffle 86 includes a downturned portion 95 which extends between the flange 94 and the inturned flange 44 of the louver section 42.

In addition it is to be noted that the lower end of the baffle 86 terminates in an outturned flange 98 which projects beneath the flange 44 of the louver section 42. These adjacent flanges may be detachably connected together by screws 100. However, a slight crack or space is left therebetween so that any water which passes through the louver units and drips down on the baffles may escape.

While the preferred embodiment of the present invention has been shown and described herein, it is obvious that many structural details may be changed without departing from the spirit and scope of the appended claims.

What I claim as new and desire to secure by Letters Patent is:

1. A vertical ventilator adapted to be mounted in an upstanding outside wall of a building comprising an upstanding rectangular shell having upstanding opposite side walls and top and bottom walls, a plurality of substantially concentric rectangular louvers of progressively decreasing dimensions disposed within and substantially concentric with said shell and respectively having upstanding side sections and top and bottom sections defining passageways having axes generally parallel to the axis of said shell, the largest of said louvers having its outer peripheral edges immediately adjacent said shell walls and secured to said shell, bracket means connected to said largest louver and supporting the other of said louvers, and a plurality of substantially horizontally disposed vertically spaced and downwardly and forwardly extending baffles fixedly mounted between said opposite side walls of said shell behind said louvers, the lowermost of said baffles extending beneath and in overlapping spaced relationship to said bottom section of said largest louver, and the uppermost of said baffles extending with an upper margin thereof not substantially above the inner margin of the top section of said largest louver.

2. A ventilator, as defined in claim 1, which includes at least three of said louvers, and support means secured to an inner margin of an intermediate louver and supporting another louver disposed inwardly of said intermediate louver.

3. A ventilator, as defined in claim 1, wherein a lower edge of said bottom section of said largest louver is spaced slightly above said bottom wall of said shell for defining an opening through which moisture and the like may escape.

4. A ventilator, as defined in claim 1, wherein said lowermost baffle extends substantially to a forward margin of said shell.
